ATTORNEY

UNITED STATES PATENT OFFICE.

EDWARD WESTON, OF NEWARK, NEW JERSEY, ASSIGNOR TO THE UNITED STATES ELECTRIC LIGHTING COMPANY, OF NEW YORK, N. Y.

RHEOSTAT.

SPECIFICATION forming part of Letters Patent No. 340,398, dated April 20, 1886.

Application filed October 13, 1885. Serial No. 179,768. (No model.)

To all whom it may concern:

Be it known that I, EDWARD WESTON, a subject of the Queen of Great Britain, and a resident of Newark, in the county of Essex and State of New Jersey, have invented certain new and useful Improvements in Rheostats, of which the following is a specification, reference being had to the drawing accompanying and forming a part of the same.

10 My invention relates to resistance-boxes or rheostats; and it consists in a novel means for inclosing or protecting the same.

The resistance-boxes or rheostats to which my invention is applicable are those for use with dynamo-electric machines, regulators, and the like, and consists of a frame of insulating material containing a long brass or German silver or other wire connected with contact-plates. Usually the wire is in numerous coils or spirals, and sometimes it is wound on plates, rods, or tubes. To inclose or protect the coils a perforated wooden box or cover has generally been used. When a strong current is passed through the coils, they are apt to become heated; hence it is desirable to have as perfect ventilation through the box as possible, in order to cool the coils. With this in view I have devised a form of cover that is at once cheaper and more effective than those used before. This cover I make of wire-gauze, either in a single piece or in several pieces

united together so as to cover all but one side of the frame containing the coils. The frame is secured to a board or plate, by which the resistance-box is attached to the wall or other support. This is shown in the accompanying drawing, which represents a resistance-box in perspective with a portion of the casing or cover removed.

40 A is the base-board or back, by means of which the device is secured to a support.

B is a wooden or insulating frame, and C are rods of insulating material supported in this frame and having the resistance wire or wires wound on them.

45 D is a wire-gauze cover that incloses the frame and coils. It is made in one or several pieces, as may be preferred, and the meshes are of such size as to prevent access of solid particles of a size to injure the coils, but to secure a free ventilation. The arrangement of coils within the netting is immaterial.

50 What I claim is—

The combination, with an insulating-frame and resistance-coils contained therein, of an inclosing cover or casing made of wire-gauze, as and for the purpose set forth.

EDWARD WESTON.
